(57) **CLAIM**

The ornamental design for an indoor wall with built-in home appliances, as shown and described.

DESCRIPTION

FIG. 1 is a front perspective view of the indoor wall with built-in home appliances;
FIG. 2 is a front view thereof;
FIG. 3 is a rear view thereof;
FIG. 4 is a left view thereof where the right view is a mirror image;
FIG. 5 is a top view thereof;
FIG. 6 is a bottom view thereof;
FIG. 7 is a reference view showing the use state that the widgets are displayed on the front center bottom cover of the claimed design; and,
FIG. 8 is a reference view showing the state of use that the built-in home appliances are installed on the front bottom. The broken lines depict portions of the indoor wall with built-in home appliances that form no part of the claimed design.

1 Claim, 8 Drawing Sheets
